UNITED STATES PATENT OFFICE.

ISAAC SNOW, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,396,670.

Specification of Letters Patent. Patented Nov. 8, 1921.

Application filed June 11, 1920. Serial No. 388,277.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings 10 representing like parts.

This invention relates to feeler mechanisms for looms, whereby replenishment of filling is effected when that in the shuttle reaches a degree of substantial exhaustion.

15 The present feeler mechanism is an improvement on the type known as the "side swipe" feeler mechanism, and one of the objects of the present invention is to provide a feeler mechanism of the side swipe type in which the feeler will be more sensitive to the presence or substantial absence of filling in the shuttle, and effect replenishment of filling only when substantial exhaustion occurs.

25 In the present invention, the feeler is mounted loosely upon a feeler carrier, and between the feeler and feeler carrier guiding means is provided which, when the feeler is moved frontwardly relative to the feeler 30 carrier on a detecting beat, will effect lateral or side swipe movement of the feeler in a direction longitudinally of the shuttle. The particular form of guiding means between the feeler carrier and the feeler consists, in 35 the present instance, of cams and projections, the one on the feeler and the other on the feeler carrier, which are arranged to give to the feeler its lateral or side swipe movement when it is moved frontwardly relative 40 to the feeler carrier.

The above and other novel features of the invention will hereinafter be described in connection with the accompanying drawings which show one good, practical form 45 of the invention, and then the novel features of the invention will be defined by the claims.

The replenishing mechanism and the train 50 of devices between the feeler and replenishing mechanism which causes the latter to effect replenishment of filling when the feeler detects substantial exhaustion of filling in the shuttle, is not herein shown and described, because it is and may be of the

usual and well-known type. The entire 55 train of mechanism between the feeler and the replenishing mechanism or the parts which set the replenishing mechanism into operation when the feeler is moved laterally on a detecting beat, may be of any appropriate character and construction, a number of such trains of mechanism being well known in the present state of the art.

In the drawings:

Figure 1 is a plan view showing the feeler 65 mechanism and its action when a working supply of filling is present in the shuttle on a detecting beat;

Fig. 2 is a view similar to that of Fig. 1, showing the operation of the feeler mechanism when filling is substantially exhausted 70 on a detecting beat; and

Fig. 3 is a perspective view of the feeler mechanism detached.

The shuttle 1 carries the usual filling carrier or bobbin 2 on which the filling 3 is wound, and it has an opening 4 in the side wall of the shuttle through which the feeler may pass and feel for the filling. The shuttle-box with the usual slotted front wall 75 is not shown, as it may be of usual construction and is well understood by those skilled in the art.

The feeler is mounted upon a feeler carrier which is itself mounted for movement 85 toward and from the front of the loom. There are two general kinds of feeler carriers, one of which is mounted for swinging movement toward and from the front of the loom, and the other of which is 90 mounted for reciprocating or sliding movement. In the present instance of the invention, the latter type of feeler carrier is shown.

The feeler stand 5 is suitably constructed 95 for supporting the feeler and feeler carrier, and in the present instance comprises a plate having the rear and front flanges 6 and 7 which, as will presently appear, afford convenient guiding means for the 100 stems frontwardly extending from the feeler carrier and feeler. The front end portion of the feeler stand 5 is downturned as at 8, to afford a convenient means for attaching the feeler mechanism adjustably to 105 a support.

The feeler carrier consists of a plate 9 which is guided in suitable ways 10 formed

in the rear flange 6 of the feeler stand, and extending frontwardly from the feeler carrier is the stem 11 which passes through a guide opening in the front flange 7 and in front of the flange is provided with a stop in the form of a pin 12 which, when the feeler carrier is in its rearward position, abuts against the surface of the flange 7.

A spring 13 is mounted upon the stem 11 and one end of the spring bears against a shoulder 14 formed on the feeler carrier, and the other end against the rear surface of the flange 7 as at 15, the construction being such that the spring 13 normally holds the feeler carrier in its rearward feeling position.

The feeler is loosely mounted upon the feeler carrier as contra-distinguished to being pivotally supported thereby; and in order to properly confine the feeler to the feeler carrier, the latter has a cover or confining plate 16, Fig. 3, which may be spaced from the surface of the feeler carrier 9 and secured to the feeler carrier by means of the pins 17. As a further means of spacing the cover 16 from the plate 9, the former may have the downturned corner portions 18. The feeler 19 has a toothed rear end portion 20 which is adapted to engage the filling on a detecting beat, and by such engagement, prevent lateral or side swipe movement of the feeler when a working supply of filling is present in the shuttle.

Since the feeler is loosely mounted upon the feeler carrier, guiding means are provided between the feeler and feeler carrier to cause lateral movement of the feeler when it is pushed frontwardly relative to the feeler carrier on a detecting beat. In the present instance of the invention, the feeler is provided with cam portions 21 and 22, one at each side of the longitudinal axis of the feeler. Mounted upon one of the pins which connect the cover 16 to the feeler carrier is a roller 23 which normally is seated in the cam 21 of the feeler; and similarly mounted upon one of the pins 17 is another roller 24 which is normally seated in the cam 22, the two cams 21 and 22 being separated longitudinally or lengthwise of the feeler and at opposite sides thereof. From the construction thus far described, it will be apparent that should the feeler 19 be pushed frontwardly relatively to the feeler carrier, the cams and projections between the feeler and feeler carrier will cause the feeler to be moved laterally. Opposite the roller 23 one of the pins 17, heretofore described, bears against the opposite inclined surface of the feeler at 25, the rear surface of the feeler being formed into a stop 26 which, when the feeler moves frontwardly, limits the extent of its frontward movement relative to the feeler carrier.

Another one of the pins 17, about central of

the feeler carrier between the rolls 23 and 24, serves to limit the extent of lateral movement of the feeler when it is moved frontwardly. The pins 17 just described, and the rollers upon these pins coöperate with the feeler to limit its movement upon the feeler carrier.

The feeler 19 is normally held in its rearward feeling position under the action of a spring, the tension of which, however, is lighter than the spring 13 heretofore described as holding the feeler carrier in its rearward position. In the present instance the feeler has connected to it at 27, a frontwardly-extending stem 28 which passes through an opening in the front flange 7 of the feeler stand, and interposed between a shoulder 29 of the stem and the rear face of the flange 7 is the light spring 30 which normally acts to hold the feeler in its rearward feeling position relative to the feeler carrier. Connected to the feeler at 31 is the transmitter 32 which controls the operative or inoperative position of the train of mechanism which effects replenishment of filling.

The cam surface 21 and the surface 25 on the feeler, as hereinbefore described, may be conveniently formed on an incline portion 33 of the feeler, as indicated in Figs. 1 and 2.

When a working supply of filling is present in the shuttle on a detecting beat, the toothed engaging end 20 of the feeler sinks into the filling and is held thereby from lateral movement, the effect being that the frontward push upon the feeler 19 acts through the cams and rollers or guiding means between the feeler and feeler carrier to force the feeler carrier frontwardly coincident with the frontward movement of the feeler, which of course remains in its undisturbed lateral relation to the feeler carrier. When, however, the filling in the shuttle has reached a degree of substantial exhaustion and is no longer capable of preventing lateral or side swipe movement of the feeler, the feeler will be pushed frontwardly as before; but as its rear end is no longer held from lateral movement by the filling, the guiding means between the feeler and feeler carrier permit the feeler to be moved laterally under the frontward pressure exerted upon it, substantially as indicated in Fig. 2. When the feeler is thus moved laterally by its frontward movement relative to the feeler carrier, it acts through the transmitter 32 to effect replenishment of filling.

What is claimed is:—

1. In a feeler mechanism for looms, the combination of a feeler carrier mounted for movement toward and from the front of the loom, a feeler loosely mounted on the feeler carrier and having two cam surfaces one on each side of the feeler, rollers mounted on the feeler carrier at opposite sides of the

- feeler and normally engaging the cams and effecting lateral movement of the feeler relative to the feeler carrier when filling is substantially exhausted on a detecting beat.
- 5 2. In a feeler mechanism for looms, the combination of a feeler carrier mounted for movement toward and from the front of the loom, a feeler loosely mounted on the feeler carrier and having its longitudinal axis ex- 10 tending in the direction of movement of the carrier, cams and coöperating projections between the feeler and feeler carrier disposed longitudinally of the feeler and constructed and arranged to cause side swipe 15 movement of the feeler relative to the feeler carrier when the filling is substantially exhausted on a detecting beat.
3. In a feeler mechanism for looms, a feeler carrier mounted for movement to- 20 ward and from the front of the loom, a feeler loosely mounted on the feeler carrier, a cam and a projection, one on the feeler and the other on the feeler carrier, constructed and arranged to cause a lateral movement of 25 the feeler when the feeler is moved front- wardly independently of the feeler carrier, and means for effecting replenishment of filling when by reason of relative movement of the feeler and feeler carrier the cam and 30 projection cause movement of the feeler longitudinally of the shuttle.
4. In a feeler mechanism for looms, a feeler carrier mounted for movement toward and from the front of the loom, a feeler 35 loosely mounted on the feeler carrier, a cam and a projection, one on the feeler and the other on the feeler carrier, constructed and arranged to cause a lateral movement of the feeler when the feeler is moved frontwardly 40 independently of the feeler carrier, and a stop to limit the frontward movement of the feeler relative to the feeler carrier.
5. In a feeler mechanism for looms, the combination of a feeler support, a feeler 45 mounted on the support for movement longitudinally of the shuttle and held from such movement by engagement with the filling until substantial exhaustion thereof, sets of cams and projections at opposite sides of 50 the feeler, one set on the feeler and one on the feeler support, and acting upon the feeler to effect movement of the feeler longitudinally of the shuttle on a detecting beat when the feeler fails to be held from such 55 movement by a working supply of filling on a detecting beat.
6. In a feeler mechanism for looms, the combination of a feeler carrier mounted for movement toward and from the front of 60 the loom, a feeler loosely mounted on the feeler carrier, interengaging guiding means at separated points frontwardly along the feeler and between the feeler and feeler carrier constructed and arranged to effect lat- 65 eral movement of the feeler when it is moved frontwardly relative to the feeler carrier, and means normally acting to yieldingly maintain the feeler rearwardly relative to the feeler carrier.
7. In a feeler mechanism for looms, the combination of a feeler carrier, a spring normally acting to hold it in rearward position, a feeler loosely mounted upon the feeler carrier for bodily movement relative thereto, cams and projections formed on the 75 feeler and feeler carrier at different distances from the rear end of the feeler constructed and arranged to effect lateral movement of the feeler when the feeler is moved bodily in a frontward direction relative to 80 the feeler carrier.
8. In a feeler mechanism for looms, the combination of a feeler carrier, a spring normally acting to hold it in rearward position, a feeler loosely mounted upon the 85 feeler carrier for bodily movement relative thereto, cams and projections formed on the feeler and feeler carrier at points separated longitudinally of the feeler constructed and arranged to effect lateral movement of the 90 feeler when the feeler is moved bodily in a frontward direction relative to the feeler carrier, and stops for limiting the relative movements of the feeler and feeler carrier.
9. In a feeler mechanism for looms, the combination of a feeler carrier mounted for movement toward and from the front of the loom, a feeler loosely mounted on the feeler carrier, cams and projections on the 95 feeler and feeler carrier separated a dis- 100 tance lengthwise of the feeler and adapted to cause lateral movement of the feeler when it is moved frontwardly relative to the feeler carrier, a spring normally acting to hold the feeler projected rearwardly 105 with the cams and projections in engagement, stops for limiting the rearward and frontward movements of the feeler relative to the feeler carrier.
10. In a feeler mechanism for looms, the combination of a feeler carrier mounted for movement toward and from the front of the loom, a feeler mounted for limited bodily and lateral movements on the feeler carrier and having an inclined portion, and 115 projections from the feeler carrier which are normally engaged with the inclined portion at opposite sides of the feeler and which in coöperation with the inclined portion of the feeler effect lateral movement 120 of the feeler when it is moved frontwardly relative to the feeler carrier.
11. In a feeler mechanism for looms, the combination of a feeler carrier mounted for movement toward and from the front of the loom, a feeler mounted for limited 125 bodily and lateral movements on the feeler carrier and having an inclined portion, projections from the feeler carrier which are normally engaged with the inclined 130

portion at opposite sides of the feeler and which in coöperation with the inclined portion of the feeler effect lateral movement of the feeler when it is moved frontwardly 5 relative to the feeler carrier, and a transmitter connected to the feeler.

12. In a feeler mechanism for looms, the combination of a feeler carrier mounted for movement toward and from the front of the 10 loom, a feeler mounted for limited bodily and lateral movements on the feeler carrier and having an inclined portion, projections from the feeler carrier which are normally engaged with the inclined portion 15 at opposite sides of the feeler and which, in coöperation with the inclined portion of the feeler effect lateral movement of the feeler when it is moved frontwardly relative to the feeler carrier, a spring normally 20 acting to hold the feeler carrier in rear position, and a lighter spring independently acting on the feeler to normally

hold the feeler in rear position on the feeler carrier.

13. In a feeler mechanism for looms, a 25 feeler supporting member, a feeler loosely mounted thereon for movement toward and from the front of the loom and longitudinally of the shuttle and adapted to be held by the filling from moving longitudinally 30 of the shuttle on a detecting beat until the filling is substantially exhausted, cam surfaces upon opposite sides of the feeler, and spaced from each other longitudinally of the feeler, and projections upon the feeler 35 supporting member coöperating with said cam surfaces to move the feeler longitudinally of the shuttle when upon a detecting beat the filling fails to hold the feeler from its side swipe movement. 40

In testimony whereof, I have signed my name to this specification.

ISAAC SNOW.
